CLAIM

The ornamental design for a supportive undergarment, as shown and described.

DESCRIPTION

FIG. 1 is a top, front, left-side, perspective view of a supportive undergarment;

FIG. 2 is a top, rear, left-side, perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof;

FIG. 8 is a bottom view thereof; and,

FIG. 9 is a left-side, cross sectional view thereof.

The broken line showing of a human user in the figures are for the purpose of illustrating environmental structure and form no part of the claimed design. The broken line showing of stitching of the supportive undergarment in the figures are for the purpose of illustrating portions of the supportive undergarment and form no part of the claimed design.
